UNITED STATES PATENT OFFICE.

CHARLES A. JOHNSON, OF SACRAMENTO, CALIFORNIA.

DISHWASHING MACHINE.

Application filed May 20, 1925. Serial No. 31,648.

This invention appertains to a novel machine for washing dishes and the like and the primary object of the present invention is to provide a machine embodying a pair of relatively long rotating brushes extending the full length of the machine and novel means for conveying the articles to be washed between the brushes, the brushes being of such a length as to insure the proper cleaning of the dishes.

Another object of the invention is to provide oppositely rotating brushes extending the full length of the washing machine disposed at an angle to the horizontal and an endless conveyor for carrying the dishes between the brushes and for gradually carrying the dishes from out of the cleansing fluid to a point above the same, the angle and length of the brushes insuring the positive cleaning of the dishes over the entire area thereof irrespective of the size of the dishes.

A further object of the invention is to provide a dish washing machine embodying a movable frame supporting a suitable tank or tub for receiving the cleansing fluid with means for maintaining the fluid in a hot condition, the tank or tub having mounted directly therein a conveyor for the dishes and the cleaning brushes.

30 A further object of the invention is to provide a novel brush arranged at one end of the tub and between the longitudinally extending brushes for cleaning the interior and exterior of glasses, cups and the like.

35 A further object of the invention is to provide novel means for guiding the cup cleaning brush during the rotation thereof, so as to insure the effective cleaning of the said cups and glasses.

40 A further object of the invention is the provision of novel means for synchronously rotating the longitudinally extending brushes, the cup and glass washing brush and the conveyor from a prime mover mounted upon the frame of the machine below the tank or tub.

45 A still further object of the invention is to provide a novel dish washer of the above character, which will be durable and efficient in use, one that will be simple and easy to manufacture and one which can be placed upon the market at a reasonable cost.

50 With these and other objects in view, the invention consists in the novel construction, arrangement and formation of parts, as will be hereinafter more fully described and

claimed, and illustrated in the accompanying drawings, in which drawings:

Figure 1 is a side elevation of the improved dish washing machine showing the covers in their open extended position for supporting the soiled dishes at one end and the clean dishes at the other end, 60

Figure 2 is an end elevation of the improved machine, 65

Figure 3 is a similar view looking from the opposite end of the machine,

Figure 4 is a fragmentary longitudinal section through the machine showing one end thereof with the cover in its open extended 70 position to form the shelf,

Figure 5 is a similar view showing the opposite end of the machine with its cover in an extended position to form the shelf,

Figure 6 is a fragmentary end elevation of the improved machine with the cover in its open extended position and in section, illustrating the novel means for detachably holding the longitudinal brushes in position and the support therefor, 75

Figure 7 is a transverse section through the improved machine illustrating the novel means for operating the longitudinally extending brushes and the cup and glass washing brush, the longitudinally extending 85 brushes being removed to facilitate the understanding of the drive,

Figure 8 is an enlarged detail section through the operating means for the cup and glass washing brush, the manipulating 90 and guide handle for the brush being shown removed from the shank,

Figure 9 is a detail fragmentary transverse section through the machine illustrating the drive for the conveyor, 95

Figure 10 is an enlarged detail section showing the drive for one of the stub shafts for one of the longitudinally extending brushes,

Figure 11 is a detail transverse section 100 illustrating the means for operating the drive chain from the pulley wheel.

Referring to the drawings in detail, wherein similar reference characters designate corresponding parts throughout the several views, the letter A generally indicates the improved dish washing machine, which comprises a frame 10, for supporting the tub or tank 15 for receiving the dishes to be washed. The frame 10 comprises corner standards 11 110 preferably formed of angle iron, with the flanges disposed inwardly. These corner

standards 11 can be braced in any desired way and are connected adjacent to their lower terminals by longitudinally extending side bars 12 which can be also formed of angle iron. The legs are also connected by end transverse angle bars 13 and the transverse and longitudinally extending angle bars 13 and 12 can support suitable brackets and the like for receiving various operating parts of the machine. If desired one of the longitudinally extending bars 12 can be set inward of the corner legs as clearly shown in Figure 7 of the drawings, in order to form a more efficient support for various parts of the device.

The tank or tub 15 can be made of sheet metal and is received between the flanges of the corner standards 10 adjacent to the upper side thereof and secured thereto by the use of suitable bolts or the like 16. The upper edge of the tub can be braced by relatively light angle bars 17 if desired. The tub or tank 15 adjacent to one end can be provided with an outlet pipe 18 in order to facilitate the draining of the cleaning fluid from the tub after the washing operation and this outlet pipe 18 can have incorporated in the length thereof a suitable globe valve or the like 19 to control the flow of water therethrough. The tub is adapted to have the dishes introduced into the same at one end thereof and the opposite end has the end wall 20 thereof terminating short of the top of the side walls 21 in order to facilitate the removal of the dishes from the tub and the corner standards 11 end at the upper edge of the said end wall 20. Cover plates 22 and 23 are provided for the upper end of the tub and the cover plate 22 is hinged as at 24 to the end angle bar 17 for the upper edge of the tub. The other cover plate 23 is hingedly connected as at 25 to a swinging section 26, which is in turn pivotally connected by hinges 27 to the upper edge of the end wall 20 and the swinging section 26 forms a continuation of said end wall 20 when the covers 22 and 23 are in their closed position over the tub. The longitudinal and outer transverse edges of the cover plates 22 and 23 are preferably rolled as at 28 and a suitable reinforcing wire can be provided for the rolled edge thereof. These cover plates are of such a size as to completely overlie the upper side of the tub and to meet at the transverse center thereof. When the cover 22 is swung to its open position at right angles to the end wall which carries the same, the said cover plate is adapted to form a shelf or support for the soiled dishes prior to the introduction of the same in the machine and in order to hold the cover plate 22 in an extended position, the outer face thereof is provided with brackets 29 which are adapted to be engaged by a swinging bracket 30 carried by the adjacent corner standard. The swinging bracket 30 is of a substantially U-shape and the connecting por-

tion thereof is adapted to engage said bracket 29. When the cover plate is in its normal position over the tub the bracket 30 can be swung to a lower position as shown in Figure 3 of the drawings.

70

The outer face of the cover plate 23 carries suitable brackets 31 and these brackets extend beyond the edge of the cover plate adjacent to the swinging section 26 and are adapted to engage said section when the cover plate 23 is in its open extended position at right angles to the wall 20. The opposite terminals of the brackets 31 are provided with angular extending feet 32 which are adapted to be engaged by a swinging U-shaped bracket 33 carried by the adjacent corner standards 11. This swinging bracket 33 can be swung to a lowered position similar to the swinging bracket 30, as shown in Figure 2 of the drawings. The cover plate 23 and the swinging section 26 constitute a shelf, when in their extended position for supporting the clean dishes as the same are brought from out of the tub.

130

Arranged longitudinally within the tub or tank 15 is an endless conveyor 35 for the dishes and this conveyor is arranged at an angle to the horizontal with its highest end terminating slightly above the upper edge of the end wall 20, so as to facilitate the delivering of the washed dishes to the swinging section 26 and the cover plate 23. Said endless conveyor 35 embodies parallel sprocket chains 36 which are trained over sprocket wheels 37 which are keyed or otherwise secured to transversely extending shafts 38 and 39. The sprocket chains 36 are connected by transverse flights or cleats 40 and every other flight or cleat 40 can be provided with a rubber or other friction pad 41 for insuring the carrying of the dishes through the tub or tank.

In order to hold the endless conveyor in proper position a supporting frame 42 is arranged directly within the tub or tank 15 and this supporting frame 42 includes inclined longitudinally extending angle bars 43 which can be bolted to side walls 21 of the tub. The lower terminals of the angle bars 43 can be connected together by a cross angle bar 44. The longitudinally extending angle bars 43 of the supporting frame 42 carry suitable bearings for receiving the shafts 38 and 39 and as is clearly shown in Figure 9 the shaft 39 has one end thereof extended through one of the side walls 21 of the tub into a gear casing 45 which is utilized for housing a drive mechanism for the said shaft, as will be hereinafter more fully described. The tub or tank 16 is adapted to be filled with water charged with soap up to the desired level, which can be just below the shaft 39 of the endless conveyor 35. If preferred the side bars 43 of the frame 42 can be braced by a transverse strip 46 as shown in Figure 5 of the drawings. The endless conveyor is arranged in the central portion of the tub and terminates short of the side

walls thereof and suitable hinged covers 47 and 48 can be connected to the side walls of the tub or to the bars 43 of the frame 42 for engaging the longitudinal edges of the upper 5 run of the endless conveyor. These plates can be swung to their raised positions so as to permit the interior of the tub to be readily reached for cleaning purposes.

In order to drive the conveyor belt, and 10 other operating parts of the machine as will be hereinafter more fully described, an electric motor 50 of the desired horse power is arranged upon the frame 10 below the tub 15. This motor can derive its energy from 15 the ordinary house current. As shown a transverse angle bar 51 is arranged in spaced parallel relation to one of the end angle bars 13 and the motor is bolted to said bar 51 and adjacent end angle bar 13. The armature 20 shaft 52 of the motor is provided with a relatively small pulley wheel 53 which is in direct alinement with a relatively large drive pulley wheel 54, which is keyed or otherwise secured to a transversely extending shaft 55 carried 25 by brackets 56 secured on the longitudinally extending beams 12. These pulley wheels 53 and 54 have trained about the same a drive pulley belt 57 for transmitting motion from the motor to said shaft 55. The shaft 55 has 30 keyed or otherwise secured thereto a sprocket wheel 58 which is disposed in the lower end of the gear casing 45. This sprocket wheel is in alinement with a relatively large sprocket wheel 59 keyed or otherwise secured to the shaft 39 of the endless conveyor. 35 A suitable sprocket chain 60 is housed within the casing 45 and is trained about the sprocket wheels 58 and 59 and it is obvious from this construction that the conveyor will be driven 40 directly from the motor. The conveyor is operated in such a manner, that the upper run thereof will move toward the end wall 20, so as to deliver the dishes on to the swinging section 26 and the cover section 23. Arranged longitudinally within the tub or tank 45 are the cleaning brushes 61 and 62 and these brushes extend the full length of the conveyor belt and are arranged at the same angle to the horizontal as said belt. The 50 brushes are arranged in parallel relation and in relatively close proximity so that the tufts thereof will engage during the rotation of the brushes and these brushes are adapted to rotate in opposite directions, by means, which will be hereinafter more fully described. These brushes are mounted in a novel manner so that the same can be removed from the tank without difficulty and thus permit the ready cleaning thereof as is clearly shown 55 in Figure 10. The lower ends of the brushes carry suitable sockets 63 which are of a polygonal configuration in cross section and these sockets are adapted to be removably fitted upon polygonal stub shafts 64, which 60 are rotatably carried by bearings 65 sup-

ported on transversely extending brackets 66 which can be bolted or otherwise secured to the side bars 43 of the supporting frame 42. Suitable stop collars 67 are keyed or otherwise secured to the stub shafts 64 for engaging the bearings 65 in order to prevent longitudinal movement of the said shafts in the bearings. The opposite ends of the shafts 64 have keyed or otherwise secured thereto beveled drive gears 68 which also engage bearings 65. These beveled gears 68 mesh with facing beveled gears 69, which are keyed or otherwise secured to a transversely extending shaft 70 mounted in suitable bearings 71. These bearings 71 are bolted to upright angle 75 irons 72 which can be bolted to the sides 21 of the tub or tank 15. The shaft 70 has keyed to the opposite end thereof sprocket wheels 73 and 74 and the sprocket wheel 73 is in alinement with a sprocket wheel 75 keyed or otherwise secured to the lower shaft 38 of the endless conveyor 35. A suitable sprocket chain 76 is trained about the sprocket wheels 73 and 75 and serves to drive the stub shafts 64 from the conveyor belt. The upper ends 80 of the brushes are supported in a novel manner and the opposite ends of the brushes from the sockets 63 are provided with spindles 77 which are rotatably mounted in bearings 78. These bearings 78 are removably carried by inwardly directed arms 79, the lower terminals of which can be bolted to the side bars 43 of the supporting frame 42. As clearly shown in Figures 6 and 9 of the drawing, the bearings 78 are provided with legs 100 85 90 which are fitted against the arms 79 and suitable bolts and wing nuts 81 and 82 are provided for securing the legs to the arms. It is obvious that when it is desired to move the brushes 61 and 62 from the tub that it is merely necessary to unthread the nuts 82 from off of the bolts 81 and swing the legs 80 of the bearings 78 from out of engagement with the arms 79, after which the brushes can be pulled outwardly by sliding the sockets 63 from off of the polygonal ends of the stub 95 100 105 shafts 64.

Novel means has been provided for washing the interior of cups and glasses and this means embodies a swinging brush 85 which is of a convenient shape to be readily inserted in cups, glasses, bowls and the like. The brush 85 can be arranged at the inner ends of the brushes 61 and 62 and the upper end thereof carries a threaded socket 86 which is adapted to be threaded on a shank 87 carried by a head 88. This head 88 is secured to a beveled drive gear 89 as can be readily seen by referring to Figure 11 of the drawings. Arranged above the gear 89 is a block 90, which is mounted for swinging movement upon a cross shaft 91, which is arranged above the shaft 70. This shaft 91 is rotatably carried by bearings 92 which are bolted or otherwise secured to the upright angle bars 72, which is also utilized 115 120 125 130

for carrying the bearings 71 as hereinbefore described. This shaft 91 has keyed or otherwise secured thereto a sprocket wheel 93 which is in alinement with the sprocket wheel 74 keyed to the shaft 70 and these sprocket wheels 74 and 93 have trained about the same a drive sprocket chain 94 which serves to drive the shaft 91 from the shaft 70. This block 90 carries a depending rigid stub shaft 95 on which is rotatably mounted the drive beveled gear 89 hereinbefore mentioned. As shown the rigid stub shaft 95 can have secured thereto a collar 96 which is fitted within the head 88 and which engages the beveled gear 89 to hold the same in position. The beveled gear 89 is adapted to mesh with the drive bevel gear 97 keyed or otherwise secured to the shaft 91 and it can be seen that the brush 85 will be driven from the shaft 91 irrespective of the position thereof relative to the brushes 61 and 62. In order to facilitate the swinging of the block 90 to change the angle of the brush 85, so that the same can be readily inserted in a cup or glass, the upper face of the block which is diametrically opposite the rigid stub shaft 95 is provided with a shank 98 on which can be removably fitted a manipulating handle 99.

A sheet metal shield 100 is provided at the end of the tub or tank which carries the brush 85 for protecting the user of the brush from coming in contact with the sprocket chain 94, shaft 91 and other operating parts of the device and this shield 100 can be secured to the side walls 15, the adjacent end walls of the tub and to the upright supporting angle bars 72. The shield is provided with suitable openings 101 and 102 through which the shank 98 and brush 85 are adapted to protrude.

In order to maintain the cleaning fluid in the tank or tub in a warm condition a gas burner, of any desired character, 103 is arranged below the tank and is mounted upon suitable supports 104, which can be bolted to the supporting frame 10. One end of the burner 103 is provided with a control cock 104 and a suitable flexible gas tube 105 is adapted to be connected therewith. This tube can lead to any suitable source of gas supply.

In operation of the improved dish washing machine, the desired quantity of water and soap is placed in the tank, and the covers 22 and 23 are arranged as shown in Figure 1 of the drawings. The dishes to be washed are placed upon the cover 22 and are introduced one at a time between the brushes 61 and 62 at the lowermost end thereof. The conveyor belt draws the dishes through the water and between the oppositely rotating brushes 61 and 62 which effectively cleans the dishes of all the grease. As the dishes are brought to the top surface of the water by the belt the same are grasped and placed upon the cover 23 of the swinging section 26 to drain. When cups, bowls or glasses are to be washed, the handle

99 is placed on the shank 98 and the brush 85 is swung to a raised position and placed within the cup or glass to be washed. The rotation of this brush will effectively clean the interior of the bowl or cup after which the same can be placed upon the conveyor belt which will draw the same between the brushes 61 and 62 and deposit the said cup or bowl on the shelf 26. During the dish washing operation, the gas burner 103 can be utilized if so desired and when the dishes have been washed, it is merely necessary to place a bucket under the outlet pipe 18 and allow the water to drain from the tub into the bucket by turning off the valve 19.

Owing to the fact that the brushes can be readily removed from the tub and the shields 47 and 48 can be swung to an upright position, it can be readily seen that the entire dish washing machine can be easily cleaned when necessary or desirable.

Changes in details may be made without departing from the spirit or the scope of this invention, but:

What I claim as new is:

1. A dish washing machine comprising a frame, a liquid container mounted upon the frame, rotatable parallel brushes disposed in the container and in contact with one another, and means cooperating with the brushes for carrying the dishes to be washed on edge through the tub and between the brushes.

2. A dish washing machine comprising a fluid container, a pair of parallel brushes arranged in the container at an angle to the horizontal and gradually leading toward the upper edge of the container, means for rotating the brushes in opposite directions, and means for conveying the dishes to be washed through the cleaning fluid in the container and between the brushes, the brushes being arranged in contact for supporting the dishes on edge upon the conveying means.

3. A dish washing machine comprising a container, a shaft, means for rotating the shaft, a block rockably mounted upon the shaft, a stub shaft rigidly carried by the rockable block, a head rotatably mounted upon the stub shaft, a brush secured to the head and means for rotating the head from said first shaft irrespective of the position of the block upon the said shaft.

4. In a dish washing machine, a cleaning fluid container, a pair of oppositely rotatable longitudinally extending brushes disposed within the container, pintles carried by one of the ends of the brushes, the opposite ends of the brushes having sockets, transversely extending brackets disposed within the container adjacent to one end thereof, bearings mounted upon the brackets, stub shafts rotatably mounted within the bearings provided with polygonal inner ends adapted to fit within the sockets carried by the brushes, upright standards in the casing, a transversely

extending shaft rotatably carried by the standards, means for operating the shaft, facing bevel gears on said transversely extending shaft, bevel gears on said stub shafts meshing with the facing bevel gears, and means detachably and rotatably receiving the pintles of the brushes.

5. In a dish washing machine, a cleaning fluid container, a pair of longitudinally extending brushes disposed in the container, pintles carried by the uppermost ends of the brushes, the lowermost ends of the brushes having sockets, inwardly extending arms arranged at one end of the container, detach-

able bearings secured to the arms for rotatably receiving the pintles, transversely extending brackets arranged adjacent to the other end of the container, bearings secured to the brackets, stub shafts rotatably mounted in the last mentioned bearings provided with polygonal inner ends for detachably fitting in the sockets, a transverse shaft, means for rotating the stub shafts and the transverse shaft, a motor, and means for operating the transverse shaft from the motor.

15 20 25
In testimony whereof I affix my signature.

CHARLES A. JOHNSON.
